UNITED STATES PATENT OFFICE.

WILLIAM M. EVANS, OF TAMPA, FLORIDA.

SAFETY-RAZOR AND BLADE-HOLDER.

1,288,854.

Specification of Letters Patent. Patented Dec. 24, 1918.

Application filed May 10, 1918. Serial No. 233,799.

To all whom it may concern:

Be it known that I, WILLIAM M. EVANS, a citizen of the United States, residing at Tampa, in the county of Hillsborough and 5 State of Florida, have invented certain new and useful Improvements in Safety-Razors and Blade-Holders; and I do hereby declare the following to be a full, clear, and exact description of the invention, such as will enable others skilled in the art to which it 10 appertains to make and use the same.

The present invention relates to improvements in safety razors and blade holders, and has for an object to provide a combination device which is useful both as a razor for shaving purposes and in addition adapted to serve as a holder for blades during stropping operations.

In the accompanying drawings forming a 20 part of this application, and in which similar reference symbols indicate corresponding parts in the several views:

Figure 1 shows a side view of a combined safety razor and blade holder provided in 25 accordance with the present invention.

Fig. 2 is a bottom edge view of the same.

Fig. 3 is a horizontal sectional view taken on the line 3—3 in Fig. 1.

Fig. 4 is a side elevational view showing 30 the parts opened out.

Fig. 5 is a vertical sectional view taken on the line 5—5 in Fig. 1.

Fig. 6 is a similar view taken on the line 6—6 in Fig. 1.

Fig. 7 is a view similar to Fig. 4 with the blade and guard removed.

Fig. 8 is a perspective view of the elongated bar.

Fig. 9 is a similar view showing the two 40 short bars.

Fig. 10 is a side elevational view, partly broken away, and showing the device for use as a blade holder for stropping purposes.

Fig. 11 is a vertical sectional view taken 45 on the line 11—11 in Fig. 10.

Fig. 12 is a side view of an improved blade useful with the present invention.

Fig. 13 is a sectional view along the line 13—13 in Fig. 12.

Fig. 14 shows a side view of an improved 50 guard used in connection with the present invention; and

Fig. 15 is a sectional view taken on the line 55 15—15 in Fig. 14.

Referring more particularly to the draw-

ings, 1 designates an elongated bar provided with a central elongated slot 2, a cut-away portion 3 along its lower edge and burs 4 projecting at right angles therefrom on the opposite side to that in which the cut-away 60 portion 3 is made.

A relatively short bar 5 is pivoted as indicated at 6 at one end of said elongated bar 1, and there is preferably placed between the elongated bar and said short bar 5 at the pivotal point 6 a spacing washer 7 which appears in Figs. 6 and 10. The short bar 5 is formed with perforations 8 to receive the ends of the burs 4 and with a slot 9 opening through its free end, and which is formed by 70 a relatively short upper prong 10 and an elongated prong 11 which projects a distance beyond the end of said upper prong 10.

At the opposite end of the elongated bar 1 is pivoted, as indicated at 12, a second relatively short bar 13 having a cut-away lower edge 14 of dimensions similar to the cut-away part 3 in the bar 1 and being further provided with a slot 14 at its free end formed by an upper elongated prong 15 and a lower 80 relatively short prong 16. The prongs on the free ends of the bars 5 and 13 are arranged to interfit when the bars are swung down to the lower horizontal position against the elongated bar 1 in the manner 85 which appears in Fig. 9.

A pin 17, which slides in the elongated slot 2 in the bar 1, is adapted to be received in either of the slots 9 or 14, and when so received forms a lock which prevents the short 90 bar from swinging out of the horizontal position. In Figs. 1, 2 and 3 this pin 17 is shown engaged in the slot 9 holding the short bar 5 locked; while in Fig. 10 the pin 17 is shown occupying the other slot 14 of 95 the short bar 13 which is accordingly locked in position.

A U-shaped handle 18 is carried by and serves to shift the pin 17 in the slot 2; this handle 18 being also useful to swing up in 100 either direction about said pivot 17 in order to tightly embrace the elongated bar 1 and either of the bars 5 or 13, whereby to press these bars firmly against the razor blade which is held therebetween.

All of the above parts are preferably 105 made of flexible metal which will afford a tight gripping action.

In Fig. 12 I show an improved razor blade 19 having the spaced perforations 20 adapt- 110

ed to fit over the burs 4, and also formed with a slot 21 which is received by the spacing washer 7 in the manner shown in Figs. 1 and 4. As shown in Fig. 13, this 5 blade 19 is formed with the double cutting edges and co-operates with the double guard 22 shown more particularly in Figs. 14 and 15.

Perforations 23 are provided in the guard 10 22 to enable it to be received over the burs 4, and a slot 24 in the end thereof is arranged to be occupied by the spacing washer 7. An elongated groove 25 is made in one 15 face of the guard 22, and is of such dimensions as to receive the short bar 5 in the manner shown in Figs. 5 and 6.

The operation of the invention may be briefly described as follows:

Assuming the parts to be shown as in 20 Fig. 7, the device may be used as a safety razor by first swinging the short bar 5 to the right so as to enable the blade 19 to be placed against the elongated bar 4, which is done by engaging the perforations 20 with 25 the burs 4. After the blade 19 has been put in place, the guard 22 is thereafter in a similar way fitted over the burs 4, and the short bar 5 may be then swung back to the left and brought down opposite the 30 elongated bar 1, where it will snap into the groove 25 of the guard. The pin 17 and handle 18 will, of course, be removed to the left in slot 2 to permit the short bar 5 to descend to the full horizontal position, 35 after which the pin 17 is again moved to the extreme right, as shown in Fig. 1, where it will form a lock to prevent the further swinging in either direction of said short bar 5. The handle 18 itself is now swung 40 upwardly from the position shown in Fig. 7 to that shown in Fig. 1, and it will tightly embrace the bars 1 and 5 and cause a clamping action to be exerted on the guard and blade. The device is now in readiness for 45 shaving, and after the operation the blade and guard may be removed by reversing the operations just described.

The device is also useful for sharpening 50 blades and is constructed to form a blade holder for receiving such blades as the Gillette, Durham Duplex, Ever Ready and other razor blades.

For stropping, the opposite short bar 13 is employed to clamp the blade between same 55 and the elongated bar 1. The pin 17 is moved into the slot 14 and forms a lock for said short bar 13, as indicated in Fig. 10. The handle 18 is likewise swung up to the left to embrace the bars 1 and 13, whereby 60 the blade will be tightly clamped in place.

The cut-away parts 3 and 14 in the bars 1 and 13, respectively, are provided to receive the backings 26 which are found on such razor blades as the Ever Ready blade 65 shown at 27 in Figs. 10 and 11. The co-

operation of the cut-away parts with such backing 26 also serves to hold the blade against displacement while stropping.

From the foregoing it will be appreciated that I have provided an exceedingly 70 simple implement adapted to serve both as a safety razor for shaving and a blade holder for sharpening, and which may be manufactured at small cost.

It is obvious that those skilled in the art 75 may vary the details of construction and arrangements of parts without departing from the spirit of my invention, and therefore I do not wish to be limited to such features except as may be required by the 80 claims.

I claim:

1. A device of the character described including an elongated bar, means at one end of said bar for receiving a razor blade and 85 guard, a relatively short bar pivoted on said elongated bar and adapted to clamp said blade and guard in position, a second short bar pivoted at the opposite end of said elongated bar and adapted to form with said 90 elongated bar a razor blade holder, and means whereby said short bars may be clamped tightly against said elongated bar, substantially as described.

2. A device of the character described including an elongated bar, relatively short bars pivoted at opposite ends of said elongated bar, a razor blade and guard received between said elongated bar and one of said short bars to provide a razor, said elongated bar and the other of said short bars adapted to receive a blade for stropping purposes, and a handle for clamping either of said short bars tightly against said elongated bar, substantially as described. 95

3. A device of the character described including an elongated bar, short bars pivoted to the ends of said elongated bar, a razor blade and guard received between said elongated bar and one of said short bars to provide a razor, said elongated bar and the other of said short bars arranged to receive a blade for stropping purposes, and locking means provided at the free ends of said short bars whereby to hold same in the clamping 110 position, substantially as described. 115

4. A device of the character described including an elongated bar, short bars pivoted to the ends of said elongated bar, a razor blade and guard received between said elongated bar and one of said short bars to provide a razor, said elongated bar and the other of said short bars arranged to receive a blade for stropping purposes, locking means provided at the free ends of said short bars whereby to hold same in the clamping 120 position, and means for binding either of said bars tightly against said elongated bar, substantially as described. 125

5. A device of the character described in- 130

cluding an elongated bar, a razor blade and guard received against said elongated bar, said guard having a groove therein, a short spring bar pivoted on said elongated bar 5 whereby to swing in a plane parallel with said elongated bar, said short spring bar adapted to snap into the groove in said guard when the short bar is swung to a position alongside said elongated bar, and 10 means for holding said short bar in place, substantially as described.

6. A device of the character described including an elongated bar, burs projecting from said elongated bar, a perforated blade 15 fitting over said burs, a perforated guard also fitting over said burs and having a groove therein, a short bar pivoted on said elongated bar and adapted to spring into the groove in said guard, said short bar also 20 having perforations to receive the ends of said burs, a handle adapted to clamp said short bar tightly against said elongated bar, and locking means carried by said handle and adapted to engage the free end of said 25 short bar, substantially as described.

7. A device of the character described including an elongated bar, a razor blade and guard fitted against said bar, a short bar pivoted on said elongated bar and adapted 30 to clamp said blade and guard thereagainst, said short bar having a slot in its free end, a handle for embracing said bars, and a pin carried by said handle and adapted to fit in said slot to lock the short bar, substantially 35 as described.

8. A device of the character described including an elongated bar having a slot therein, a blade and guard fitted against said bar, a second short bar pivoted on said first 40 mentioned bar and adapted to clamp said blade and guard in place, said second mentioned bar also having a slot in the end thereof, a handle adapted to embrace said bars, and a pin carried by said handle and 45 movable in the slot in said first mentioned bar, said pin adapted to engage in the slot in said second mentioned bar whereby to lock same, substantially as described.

9. In a device of the character described, a bar, a second bar pivoted to said first mentioned bar, a spacing washer between the pivoted ends of said bars, a blade having a slot therein receiving said spacing washer, a guard also having a slot therein receiving said washer, said blade and guard adapted 50 to be clamped between said bars, means for embracing said bars to hold the same in binding position on the said blade and guard, and means for locking the bars in binding position, substantially as described. 55

10. In a device of the character described, the combination of an elongated bar, a pair of short bars pivoted one at each end of said elongated bar, a razor and guard fitted between said elongated bar and one of said 60 short bars to provide a razor, the other of said short bars adapted to coöperate with the elongated bar to provide a blade holder for stropping, a swinging handle adapted to embrace said elongated bar and either 70 of said short bars, and locking means provided between the free ends of said short bars and said handle, substantially as described.

11. In a device of the character described, 75 the combination of an elongated bar having a central slot therein, burs projecting from said bar at one side of said slot, a razor blade having perforations fitted over said burs, a guard also having perforations like- 80 wise fitted over said burs, a short bar pivoted at one end of said elongated bar and also having perforations received over the ends of said burs whereby to clamp the blade and guard in position, a second short bar 85 pivoted at the opposite end of said elongated bar and providing therewith a blade holder for stropping, a handle adapted to embrace said elongated and short bars, a pin carried by said handle and movable in 90 said slot, said short bars having slots in their free ends also provided to receive said pin whereby to lock same, substantially as described.

In testimony whereof I affix my signature. 95
WILLIAM M. EVANS.
